UNITED STATES PATENT OFFICE

159,057

PAIR OF SCISSORS OR SIMILAR ARTICLE

John J. Foye, Jr., Old Greenwich, Conn., assignor to Products Development, Incorporated, Stratford, Conn., a corporation of Connecticut

Application May 21, 1949, Serial No. 2,922

Term of patent 7 years

(Cl. D22—5)

To all whom it may concern:

Be it known that I, John J. Foye, Jr., a citizen of the United States, residing at Old Greenwich,
in the county of Fairfield, State of Connecticut,
have invented a new, original, and ornamental
Design for a Pair of Scissors or Similar Article, of which the following is a specification, reference being had to the accompanying drawing, forming a part thereof.

In the accompanying drawing;

Fig. 1 is a side elevational view of a pair of scissors or similar article, showing my new design
with the device open.

Fig. 2 is a similar view with the device closed.
Fig. 3 is an end elevational view taken from the right of Fig. 1.

Fig. 4 is a sectional view taken substantially
on the line 4—4 of Fig. 1.

I claim:

The ornamental design for a pair of scissors
or similar article, substantially as shown.

JOHN J. FOYE, JR.
